(No Model.)

G. J. CAPEWELL.
BARREL OPENER.

No. 561,537.

Patented June 2, 1896.

UNITED STATES PATENT OFFICE.

GEORGE J. CAPEWELL, OF HARTFORD, CONNECTICUT, ASSIGNOR TO THE SPECIALTY MANUFACTURING COMPANY, OF SAME PLACE.

BARREL-OPENER.

SPECIFICATION forming part of Letters Patent No. 561,537, dated June 2, 1896.

Application filed March 2, 1894. Serial No. 502,156. (No model.)

To all whom it may concern:

Be it known that I, GEORGE J. CAPEWELL, a citizen of the United States, residing at Hartford, in the county of Hartford and State of Connecticut, have invented certain new and useful Improvements in Barrel-Openers, of which the following is a specification.

The invention relates to the class of tools more particularly adapted and intended for opening barrels, tubs, kegs, and the like hooped packages, although it can be used for opening other receptacles, the object being to provide a simple, cheap, and strong tool of this class which can be readily used with great power for drawing nails and other fastenings from the hoops, staves, and heads without damage, whereby the barrels or other packages are easily opened and left in good condition for further use.

Referring to the accompanying drawings, which illustrate the invention, Figure 1 is a longitudinal section of the tool. Fig. 2 is a detail view of a portion of the tool, showing the position occupied when it has a nail started from a barrel-hoop so that its head is no longer buried in the wood. Fig. 3 is a similar view showing the position with the nail still farther drawn. Fig. 4 is a top view of the nail-drawing head. Fig. 5 is a central section of the latter. Fig. 6 is a top view of a half-section of a drawing-head, and Fig. 7 is a transverse section of the head.

In the views, 1 indicates the tubular body or shank of the tool, which is preferably cast to shape of iron with the central bore that loosely holds a rammer-bar 2, that is used to drive the jaws of the drawing-head beneath the head of the nail to be extracted. This rammer preferably has a pin 3 projecting from one side into a slot 4, that is formed along the inner wall of the opening in the shank of the tool, and this pin is arranged to come in contact with the inward-projecting shoulder 5 on the latch 6, so that when the parts are in their normal position the bar will not be pulled out and entirely removed from the opening when it is being reciprocated in use to drive the jaws under the nail-head. This latch, however, is so pivoted that when the handle, which is usually formed with an opening that can be utilized for hanging the

tool on a nail, is forced against its spring the shoulder swings out of the slot and permits the removal of the rammer-bar.

In a socket formed in the end of the shank 55 of the tool is held the neck 7 of the drawing or extracting head 8. Of course this head may be formed integral with the shank of the tool; but it is preferred that it be detachable, as shown, either in one piece or in two parts 60 divided, as indicated by the dotted line in Fig. 4 and by Fig. 6, and held in the socket by a set-screw 9, for this allows the ready insertion of a new head when one becomes broken or worn in use, and it also permits the use of a suitable 65 fine high-grade steel for the drawing-head, with an ordinary cheap metal for the shank and body of the tool, and being obliged to use the high-grade material for only such a small part reduces the cost of the tool to a minimum. 70 This drawing-head, when viewed from the top and sides, shows as curved to a point at the front end, and when forged, dropped, or otherwise formed to shape it is provided with a curved mortise 10, which leaves lips 11 on the 75 sides. These lips are substantially parallel with each other, and the bottom of this mortise which thus separates the lips is preferably rounded, while the outer lower corners of the lips are also preferably rounded, so the 80 head in cross-section is gouge-shaped, as shown in Fig. 7, and the interior may be provided with a curved groove 12, which will extend nearly to the front end or gouge-point, where the bottom of the mortised part be- 85 tween the lips is cut away, forming a mouth 13, that bifurcates the end of the head, forming two short jaws 14, which mouth, however, does not usually extend inward from the end to the jaw-fulcrum or to where the taper or 90 curve for the end of the bottom edge commences. This construction forms a head with a pair of substantially parallel lips that are completely separated at their points and are joined along their fulcrum edge by a web that 95 gradually increases in thickness, which edge-wise lips provide wide stiff flanges that strongly hold the pulling-jaws and strengthen them where they are made thin and gouge-shaped, so as to pass under the head of a nail. 100

On the shank of the tool near the drawing-head is a projection, boss, or stud 15, that

performs the function of a fulcrum for use when drawing a nail, and this projection can be so formed that it may be utilized for driving nails into a barrel or other structure when so desired.

- To open a barrel, tub, keg, or the like package or to remove a hoop either on the exterior or interior of the staves, the pointed end of this tool is placed up to the head of the nail to be drawn obliquely to the surface in which the nail is driven and by a few blows of the rammer forced under the head of the nail, the gouge-shaped end of the drawing-head chiseling diagonally across the grain of the hard-wood hoop or stave beneath the nail-head, the shank of the nail passing into the mouth 13 between the lips, so that the edges of the head of the nail lie in the mortise of the tool-head above the jaws 14. Then as the tool is rocked on the round periphery of the barrel the head rolls on the point where the taper or curve of the end begins, and, as the fulcrum is so very close to the head of the nail it is drawing, a powerful leverage results for starting the nail from the hard wood of the barrel-stave, which nail is usually clenched over on the side opposite from the head. After the nail has been started on this very powerful fulcrum the tool is in the position shown in Fig. 2. Then the projection or hammer-head comes in contact with the exterior of the barrel and forms a further fulcrum, on which the tool is rocked to complete the drawing of the nail, as shown in Fig. 3.
- This tool is very strong, as the nearly-parallel lips of the head are quite wide, and yet on account of their shape the jaws can be readily driven obliquely into the wood by the rammer under the head of the nail to be drawn, the gouge shape facilitating the chiseling of the end obliquely into the wood, while it would be impossible to drive the jaws of an ordinary puller straight into the wood about the head of a nail on account of the hardness of the wood usually used for barrel staves and hoops, and also on account of the elasticity or spring of a barrel hoop or stave.
- The tool can be very cheaply made, as the shank and rammer can be of ordinary cast metal, while the head, which can be removed and a new one substituted, if desired, can be made of the finest and best metal for the purpose. As the short fulcrum formed by the shape of the drawing-head is close to the end of the mouth that bifurcates the points of the

60 lips to form the jaws, it can be used with great power for extracting nails from barrels, tubs, kegs, and the like packages having curved surfaces, or receptacles made of hard wood, and the hammer-head, which forms the distant fulcrum for completing the extracting of the nails, once started, serves also to provide a means whereby the barrel can be headed up and nails driven into place.

I claim as my invention— 65

1. A barrel-opener consisting of a shank bearing a movable rammer with an integral fulcrum and driving-head projecting from one side and a drawing-head projecting from one end, said drawing-head having a pair of wide 70 lips that stand substantially parallel with each other, the contour of which curves to a point at the outer end from both top and bottom and also from each side, the wide parallel lips being joined together along a portion of their bottom or fulcrum edge beginning a short distance from the outer end by a web that gradually increases in thickness, substantially as specified.

2. A barrel-opener consisting of a shank 80 bearing a movable rammer with an integral fulcrum and driving-head projecting from one side and a drawing-head projecting from one end said drawing-head having a pair of lips that curve to a point from four sides and are 85 widest from top to bottom opposite the short fulcrum, the wide parallel lips being joined together along a portion of the bottom or short-fulcrum edge beginning a little distance from the outer end by a web that gradually increases in thickness, substantially as specified.

3. A barrel-opener consisting of a shank bearing a movable rammer with an integral fulcrum and driving-head projecting from one 95 side and a drawing-head projecting from one end said drawing-head having a pair of lips that curve to a point from four sides and also have their lower outer corners adjacent to where the lips are joined rounded off making 100 the bottom edge gouge-shaped, the wide parallel lips being joined together along a portion of the bottom or short-fulcrum edge beginning a little distance from the outer end by a web that gradually increases in thickness, substantially as specified.

GEORGE J. CAPEWELL.
